UNITED STATES PATENT OFFICE

ALBERT M. LEAHY, OF SOMERVILLE, AND CARLTON G. LUTTS, OF SALEM, MASSACHUSETTS, AND JAMES REID, DECEASED, LATE OF WATERTOWN, MASSACHUSETTS, BY MARGARET S. REID, ADMINISTRATRIX, OF WATERTOWN, MASSACHUSETTS

DETACHABLE CHAIN LINK

Application filed August 28, 1929. Serial No. 388,963.

This invention relates to a detachable chain link of the type disclosed by Patent No. 1,386,732, granted August 9, 1921, to Reid and Leahy. Said link comprises a C-shaped body member having an open side with cylindrical flanged projections at the ends, a pair of duplicate coupling members closing said open side, each of said coupling members having recesses for the reception of said projections, and plain abutting inner sides held in contact in the plane of said C-shaped member, and means for separably uniting said coupling members.

The present invention is characterized by certain improvements hereinafter described and claimed, relating to the coupling members and the means for uniting the said members, the object being to provide a detachable link of the character stated, the coupling members of which are more effectively united than heretofore.

Of the accompanying drawings forming a part of this specification,—

Figure 1 is a side view of a detachable chain link embodying the invention.

Figure 2 is a section on line 2—2 of Figure 1, the tapered pin shown by dotted lines in Figure 1, being shown in side elevation.

Figure 3 is a perspective view of the tapered pin.

Figure 4 is a side view, and

Figure 5 an end view of one of the coupling members shown by Figures 1 and 2.

Figure 6 is a side view, and

Figure 7 an end view of the other coupling member shown by Figures 1 and 2.

Figure 8 is a section on line 8—8 of Figure 1.

Figures 1 to 8 inclusive show the preferred embodiment of the invention, the coupling members being differently formed and not duplicates of each other.

Figure 9 is a view similar to Figure 2, showing a different embodiment, the coupling members being duplicates of each other.

Figure 10 is a side view, and

Figure 11 an end view of one of the two duplicate coupling members shown by Figure 9.

Figure 12 is an end view of one of the du-

plicate coupling members, showing the end opposite that shown by Figure 11.

Figure 13 is a section on the plane indicated by line 13—13 of Figure 9.

The same reference characters indicate the same parts in all of the figures.

The link body 14, preferably forged from an alloy, steel, is C-shaped as disclosed by said prior patent, and is provided with ends 15, between which is an open space. Each of the ends 15 is provided with projections 16, having flanges 17, at their ends forming shoulders 18.

In case the link is to be provided with a central stud, a boss 19 is formed on the side 65 of the link body opposite the open space, and is provided with a recess 20.

The link body as thus far described is substantially as disclosed by said prior patent, and the coupling members are interengaged 70 with the ends 15, and bridge the open space as heretofore.

We will now describe the preferred construction shown by Figures 1 to 8, inclusive, whereby the coupling members are united to 75 each other.

21 and 22 designate the coupling members which have plain abutting inner sides 23, and recesses 28 and 29 fitting the projections 16 and flanges 17 of the link body ends 15, so that the coupling members are interlocked with the ends of the link body as heretofore. Each coupling member has an ear projecting from its inner side, and a recess beside the ear, the ear of one member projecting into the recess of the other, so that the members are interlocked against edgewise movement in the plane of the link. In this embodiment the member 21 has a projecting ear 24, and a recess 25 beside said ear, as shown by Figures 4 and 5, and in section by Figure 2, and the member 22 has a projecting ear 26, and a recess 27 beside the same, as shown by Figures 6 and 7, and in section by Figure 2, the ears and recesses being interengaged or interlocked as shown by Figure 2. Said ears and recesses extend crosswise of the pin socket hereinafter described.

The abutting inner sides 23 of the coupling members 21 and 22 have recessed faces 30 100

and 31, forming opposite side portions of a tapered socket extending across and between the members, said faces alternating with the ears and recesses.

5 The ears 24 and 26 are provided with tapered bores 32, alined with the socket portions formed by the recessed faces 30 and 31, and constituting other portions of said tapered socket. 33 designates a tapered pin formed to have a close driving fit in the tapered socket, and prevented from withdrawal therefrom by a lead keying button or head 34, swaged into an undercut opening provided by coinciding recesses 35, formed in the abutting faces of the coupling members at the outer ends of the recessed faces 30.

20 The ear bores 32 entirely surround a portion of the pin 33, so that the ears cooperate with said pin in preventing sidewise movement of the coupling members relative to the plane of the link, and withdrawal of said members from the open side of the C-shaped body 14. The described coupling members 25 are not duplicates of each other, so far as the ears and the ear-receiving recesses are concerned.

30 The embodiment shown by Figures 9 to 13, inclusive, includes two coupling members 37, each a duplicate of the other, each having an ear 38 and a recess 39, the recess of each member receiving the ear of the other member, the form and arrangement of said ears and recesses constituting the chief differences 35 between the members being now described, and the members 21 and 22 above described.

40 The ears 38, instead of extending crosswise of the tapered socket and pin, and having continuous socket bores like the ears 24 and 26, stand at opposite sides of the pin, and have open recessed socket-forming faces 40, which bear on opposite sides of the pin, and meet so that they constitute a divided socket portion, as shown by Figure 13, and cooperate with the pin 33 in preventing sidewise movement of the coupling members relative to the plane of the link. The ears 38 may be reinforced by fillets 38a.

50 The coupling members of each embodiment have abutting projections extending across the link body 14, and provided with tapering or rounded ends entering and closely fitting the recess 20 in the body boss, the wall of said recess entirely surrounding the ends of the coupling member projections.

55 The link body is provided at its midlength with a socket extension 42, receiving the smaller end of the pin 33, so that the pin is seated both on the socket of the coupling members and on a socket extension in the link body.

60 It will be seen that the ears and recesses of the coupling members constitute an embodiment of means associated with said members for interlocking the same against

65 edgewise movement in the plane of the link, said interlocking means being adapted, as by the bores 32 or the recessed faces 40 to cooperate with the pin 33 in locking the coupling members against sidewise movement 70 relative to the plane of the link.

75 We claim:

1. A detachable chain or cable link, comprising a C-shaped body member having an open side with flanged projections at its ends, 75 a pair of coupling members closing said open side, having recesses for the reception of said projections and plain abutting inner sides, there being a pin socket between the coupling members, interlocking means associated with 80 the coupling members for interlocking the same against edgewise movement in the plane of the link, and a locking-pin inserted in said socket, said interlocking means being adapted to cooperate with said pin in locking 85 the coupling members against sidewise movement relative to the plane of the link.

2. A detachable chain or cable link, comprising a C-shaped body member having an open side with flanged projections at its ends, 90 and a pair of coupling members closing said open side, having recesses for the reception of said projections and plain abutting inner sides, and means for interlocking and uniting said coupling members, including tapered 95 pin socket portions in the abutting sides, a pair of interengaged ears projecting from said abutting sides, the ear of each member entering a recess in the other, so that the coupling members are interlocked against 100 edgewise movement in the plane of the link, said ears having socket portions alined with those in the abutting sides, the several socket portions constituting a tapered socket extending between the abutting sides and 105 through the ears, and a tapered pin inserted in said socket and engaging the ears to lock the coupling members against sidewise movement relative to the plane of the link.

3. A detachable chain or cable link, comprising a C-shaped body member having an open side with flanged projections at its ends, 110 and a pair of coupling members closing said open side, each of said coupling members having recesses for the reception of said projections and plain abutting inner sides, the link being characterized by pin-engaging 115 ears projecting from the inner sides of the coupling members into complementary recesses to interlock the coupling members against edgewise movement in the plane of the link, each member having an ear and a recess, said abutting sides and ears having socket-forming faces collectively forming a tapered socket

120 extending between the coupling members, and a tapered pin inserted in said socket, to lock the coupling members against sidewise movement in the plane of the link, the socket-forming faces of said ears being formed to 125 130

cooperate with said pin in preventing side-wise movement of the coupling members.

4. A detachable chain or cable link, comprising a C-shaped body member having an open side with flanged projections at its ends, and a pair of coupling members closing said open side, each of said coupling members having recesses for the reception of said projections and plain abutting inner sides, said coupling members having abutting projections extending across the link to form a central stud, the link body having a projection opposite its open side, provided with a recess receiving the ends of the abutting projections, the coupling members being provided with pin-engaging ears, the ear of each member projecting into a recess in the other, said abutting sides and ears having socket-forming faces collectively forming a tapered socket extending between the coupling members, the link body having a tapered socket extension, and a tapered pin inserted in said socket and socket extension.

5. A detachable chain or cable link, as specified by claim 3, the said ears extending crosswise of the tapered socket and overlapping each other, the socket portions in the ears being bores extending through the ears and entirely surrounding portions of the pin.

30 In testimony whereof we have affixed our signatures.

ALBERT M. LEAHY.
